UNITED STATES PATENT OFFICE.

HOWARD HOUSEKNECHT, OF FREELAND, PENNSYLVANIA.

SAFETY APPARATUS FOR MINE-CARS AND THE LIKE.

1,170,263.

Specification of Letters Patent.

Patented Feb. 1, 1916.

Application filed June 25, 1915. Serial No. 36,405.

To all whom it may concern:

Be it known that I, HOWARD HOUSEKNECHT, a citizen of the United States, residing at Freeland, in the county of Luzerne 5 and State of Pennsylvania, have invented new and useful Improvements in Safety Apparatus for Mine-Cars and the like, of which the following is a specification.

This invention relates to improvements in 10 safety apparatus for mine cars and the like.

In carrying out the present invention, it is my purpose to provide safety apparatus for mine cars whereby downward movement of the car on a gradient will be prevented in 15 the event of the hauling cable breaking and whereby the car will be held stationary on the trackway as long as the hauling cable is broken or slack.

It is also my purpose to provide apparatus 20 of the class described which will be held inactive as long as the hauling cable remains intact and which will be connected with such cable and operate automatically on the breaking of the cable to lock the car on the 25 trackway, thereby preventing the descent of the car on a gradient.

With the above and other objects in view, the invention consists in the construction, combination and arrangement of parts hereinafter set forth in and falling within the 30 scope of the claim.

In the accompanying drawing; Figure 1 is a bottom plan view of a mine car equipped with the safety apparatus constructed in accordance 35 with the present invention. Fig. 2 is a fragmentary longitudinal sectional view through the car and trackway. Fig. 3 is a cross sectional view on the line 3—3 of Fig. 1.

Referring now to the drawing in detail, 1, 40 1 designate the parallel lines of rails of a mine car trackway, while 2 indicates a mine car adapted to traverse the lines of rails 1, 1. Disposed between the lines of rails 1, 1 of the trackway on each inclined portion of the 45 trackway are safety rails 3 disposed adjacent to the inner sides of the respective lines of rails 1 and preferably of a height greater than the similar dimension of the track 50 rails.

In accordance with my present invention, the side sills of the car 2 at the forward end of the car are formed with transversely alining slots 4 and disposed within the slots 4 are

the ends of a draw bar 5 extending transversely of the car and equipped centrally with a U-shaped yoke 6 connected with the hook 7 on the car end of the hoisting cable 8. Passed through alining openings in the draw bar 5 and the end sills immediately behind the draw bar are bolts 9 spaced apart equal distances transversely of the car and threaded onto the forward ends of the bolts 9 are nuts 10 respectively bearing against the outer side of the draw bar 5, while threaded onto the rear end of the bolts 9 are nuts 11 respectively and surrounding each bolt 9 between the nut 11 and the rear edge of the adjacent end sill of the car is a coiled expansion spring 12 acting normally to slide the draw bar 5 toward the rear ends of the slots 4 against the action of the hauling rope. Secured to the inner edges of the respective side sills of the car at a point approximately centrally of the length of the car are depending hangers 13 and pivotally connected to the lower ends of the hangers 13 are horizontal bell crank levers 14, each having one limb projecting toward the rear end of the car and the other limb projecting toward the longitudinal center line of the car and formed on the extremities of the rearwardly projecting limbs of the respective bell crank levers are outwardly extending dogs 15 adapted to bite into the safety rails 3, 3, 85 while connected with the inner extremities of the remaining limbs of the bell crank levers through the medium of pin and slot connections 16 are the opposite extremities, respectively, of a cross bar 17. Connected with the bar 17 is a yoke 18 and projecting from the yoke 18 is a connecting arm 19 extending toward the front end of the car and having the forward extremity thereof secured to the rear end of the central bolt 9. 95

In practice, as long as the cable 8 remains taut, the springs 12 are contracted and the dog ends of the bell crank levers held out of engagement with the safety rails 3. When, however, the cable 8 breaks or becomes slack 100 the springs 12 react and slide the bolts 9 and the draw bar 5 rearwardly and in the rearward movement of the center bolt 9 a like motion is imparted to the rod 19, thereby pushing the bar 17 rearwardly with the effect to swing the bell crank levers 14 about their pivotal connections with the hangers 13 so that the dogs 15 will bite into the

safety rails 3, thereby holding the car against backward movement on the track-way.

I claim:

- 5 In safety apparatus for mine cars, safety rails disposed between the lines of rails of the mine car trackway, hangers depending from the side sills of the mine car, bell crank levers pivoted upon the lower ends of said hangers respectively and each having one limb thereof formed with a dog adapted to engage the adjacent safety rail, a transverse bar, pin and slot connections between said bar and the remaining limbs of said bell 10 crank levers, a cross bar mounted in the side sills of the mine car and capable of move- 15

ment therein longitudinally of the car, a connection between the first-mentioned cross bar and the last-mentioned bar, a connection between the last-mentioned bar and the hauling rope, and springs connected to the last-named bar and acting against the hauling rope to force the dogs into engagement with said safety rails in the event of the breaking of the hauling rope. 20 25

In testimony whereof I affix my signature in presence of two witnesses.

HOWARD HOUSEKNECHT.

Witnesses:

FOSTER HOUSEKNECHT,
SAMUEL EMERSON HOUSEKNECHT.
